UNITED STATES PATENT OFFICE.

ROY F. DOWDY, OF ROANOKE, VIRGINIA, ASSIGNOR TO SAFETY GAS LIGHTER CORPORATION, OF ROANOKE, VIRGINIA, A CORPORATION OF VIRGINIA.

ELECTRIC GASLIGHTER.

1,312,622.

Specification of Letters Patent. Patented Aug. 12, 1919.

Application filed December 22, 1917. Serial No. 208,367.

To all whom it may concern:

Be it known that I, Roy F. Dowdy, a citizen of the United States, residing at Roanoke, in the county of Roanoke and State 5 of Virginia, have invented certain new and useful Improvements in Electric Gaslighters, of which the following is a specification.

This invention relates to electric gaslighters of the type described in my U. S. Letters 10 Patent No. 1,159,908 issued Nov. 9, 1915, and the object of the same is to provide improvements in the handle and its contained parts whereby greater durability as well as simplification of manufacture may 15 be obtained. The invention consists of the formation, combination and arrangement of parts as set forth herein and particularly as pointed out in the claims.

In the drawings which show a preferred 20 embodiment of the present invention and which form a part of this specification, Figure 1 is in general a longitudinal, sectional view taken along the central axis of the handle and showing the assembled contents thereof: Fig. 2 is an end view of the outer head of the resistance unit: Fig. 3 is a detached end view of the electric connection used in connection with this head: Fig. 4 is a vertical, sectional view of the handle 25 taken on the line 4—4 of Fig. 1. Fig. 5 is an outside or plan view of the entire handle: Fig. 6 is a fragmentary section of the handle and the outer end of the resistance element, taken on the line 6—6 of Fig. 30

35. The scale of Figs. 2, 3, 4 and 6 is somewhat enlarged over that of Figs. 1 and 5 in order to show the construction more clearly.

Referring to the drawings the handle 7 40 comprises a hollow body or tube, made of an insulating material such as wood or hard rubber, its ends being closed by an integral head 8 and a removable head 9, the latter being screw-threaded to the body of the handle. Contained within this handle is a resistance element 10, leading to the outer end 45 of which is an electric wire 11 which conducts current from the ungrounded side of a house-lighting circuit as described in detail in my earlier patent above referred to. This wire passes through an opening in the outer end of the head 9 and is knotted at 12 inside the head to protect the connection between this wire and the resistance unit 50 from mechanical strains. To the inner end

of the resistance unit is attached a current-conducting leaf spring 13 which terminates near to but slightly above the inner end of the electrode 14, this latter being secured as by pressing, in a suitable opening in the 60 integral head 8 and extending through that head to the exterior. This electrode is provided with an insulating shield 15 for a portion of its length but both the inner end and the outer point of the electrode are exposed. 65

The entire resistance unit with the leaf spring attached to it are adapted to be entered in the outer end of the handle and positioned between the inner end of the resistance unit and the inner end of the electrode is a push button 16 which is disposed in and extends through the wall of the handle. This push button is constructed of insulating material and at its inner end is provided with a way or channel 17 through 70 which the leaf spring is inserted as the handle is entered, thus serving to stay the resistance unit against rotation within the handle. At the same time the leaf spring prevents the removal or loss of the push 75 button. This channel 17 is formed by bradding a fiber washer 18 to the bottom of the push button, the shims or spacers 19 at the edges serving to provide the necessary opening for the leaf spring. When the button 80 is depressed from the outside the free end of the leaf spring is brought into contact with the electrode and the circuit completed thereto.

The resistance unit 10 is formed with a 90 core or spool 20 of insulating material, having a slightly enlarged head at each end, these also being formed of insulating material. These heads are of such size as to fit snugly within the cavity of the handle. A 95 bolt 21 passes longitudinally through a central hole in the core and through both heads, the head of the bolt being let into the outer face of the outer head 22. At the inner end of the bolt and on the inner face of the inner head 23 the leaf spring 13 is secured beneath the nut 24 of this bolt and the entire device may thus be drawn firmly together by means of this single bolt. In order, however, that current may not pass through this bolt and 100 short-circuit the resistance wire the outer face of the head 22 is covered with a circular shield 25 of insulating material which entirely overlies the same and covers the bolt head. This shield is secured to the head 22 110

by means of a pair of spaced bolts 26 which are isolated from the central bolt and which pass in a reverse direction through the head 22, the heads of these bolts being slightly 5 let into the inner face of this head but preferably projecting inwardly a slight distance also in order to form anchors where they are compressed or drawn against the outer end of the core 20. By drawing up the nuts 10 27 of these bolts the shield may be secured to the head 22. This shield is made of slightly larger diameter than the cavity of the handle and its edges overlie the outer end of the same. When the head 9 is screwed 15 up the shield is firmly held in place and the entire resistance unit thus held against longitudinal displacement within the handle.

Encircling both of the bolts 26 and forming a washer for the nuts 27 is a loop 28 20 which also forms an electric connector. The end of the wire 11 terminates and is secured beneath this washer and is anchored by one of the nuts 27. Anchored beneath the other nut 27 and beneath the washer 28 25 is the outer end of a length of resistance wire 29 which then passes through slots in the edge of the shield 25 and head 22 and is wrapped in a spaced helical path upon the surface of the core 20, between the heads 30 22 and 23, the inner end of the resistance wire being secured beneath the leaf spring by means of the bolt 21. After being wrapped upon the coil 20 the resistance wire and the spool is coated with varnish or the 35 like and there is then applied over the wire a wrapper 30 of sheet asbestos or other heat insulating and current insulating material, thus maintaining the spacing of the wire upon the spool and protecting the handle 40 from noticeable heat when used for short periods only.

I have thus described an embodiment of my invention. Other embodiments within the scope of the appended claims are possible without departing from the spirit thereof.

I claim,

1. In an electric gaslighter, a tubular handle having an opening in one of its 50 ends, a removable head for normally closing the said opening and means for securing it to the handle, a resistance unit within the cavity of the handle, the same having a portion of substantially the same 55 cross section as the cavity of the handle, there being another portion at the outer end of the unit formed of greater dimension than the said cavity and adapted to overlie the end of the tube, and to restrain the unit 60 against inward movement, the said head being formed to restrain the unit against outward movement.

2. In an electric gaslighter, a tubular handle having an opening in one of its ends, 65 a removable head adapted to normally close

the said opening, means for securing the head to the handle, a resistance unit disposed within the handle, the same including a core with an insulating head at its outer end of such size as to fit snugly within the 70 cavity of the handle, means passing through the core head for securing it to the core, and a shield for covering the core head disposed on the outer face of the same and secured thereto, the said shield being formed to 75 overlie the end of the handle in such manner as to restrain the entire unit against inward movement, there being also coacting means between the shield and the head of the handle for restraining the entire unit 80 against outward movement.

3. In an electric gaslighter a tubular handle having a head at each end, at least one of which is removable, a resistance unit within the cavity of the handle and formed 85 to be entered endwise therein, means passing through the removable head for connecting the outer end of the unit with an outside source of electric energy, an electrode protruding from the opposite end of 90 the handle, a leaf spring extending from the inner end of the unit to adjacent the inner end of the electrode but normally out of contact therewith, a push button extending through the wall of the handle between 95 the unit and the electrode and adapted when depressed to deflect the leaf spring into contact with the electrode, the said push button having an opening through its lower end and the leaf spring being disposed within 100 the opening.

4. In an electric gaslighter, a resistance unit embodying a cylindrical core of insulating material pierced along its longitudinal axis, a head of insulating material 105 disposed at each end of the core, a threaded securing bolt having its head let into the outer face of one of the heads and passing therethrough and through the said hole in the core, the other head being screwed on 110 the thread of the said bolt, said bolt being supplied also with a clamping nut on the outer face of the last mentioned head, a shield of insulating material disposed over 115 the outer face of the first head and covering the bolt head, a pair of additional bolts spaced away from the said central bolt and adapted to hold the said shield against the head, a current-conducting washer encircling the two additional bolts and disposed 120 on the outer face of the shield, nuts on the outer ends of the two additional bolts, a length of resistance wire disposed on the said core between its heads, the one end of which being anchored by one of the said 125 two shield bolts, the other end being anchored by the nut on the end of the central bolt, a conducting wire connecting the resistance unit with a source of electric energy, the end of the same being anchored 130

by the other of the shield bolts, an electrode adapted to be brought into contact with the metal of a gas burner, and means for connecting the inner end of the resistance unit 5 with the electrode, said means being also anchored by the nut on the inner end of the central bolt.

5. In an electric gaslighter, a tubular handle having a removable head at one end, 10 means for securing the head to the handle, a resistance unit within the cavity of the handle, means coacting between the removable head and the outer end of the unit for

securing the unit against endwise movement within the handle, an electrode protruding from the other end of the handle, a movable element attached to the inner end 15 of the unit and adapted to be brought into electrical contact with the electrode, means extending to the exterior of the handle for 20 so deflecting the movable element, and means coacting with the last-mentioned means for preventing the rotation of the unit within the handle.

In testimony whereof I affix my signature. 25
ROY F. DOWDY.
